CLAIM

We claim the ornamental design for cap for containers of air-fresheners, insecticides, and the like, as shown.

DESCRIPTION

FIG. 1 is a top, front perspective view of a cap for containers of air-fresheners, insecticides, and the like showing the new design.

FIG. 2 is a bottom perspective view of the cap turned counterclockwise.

FIG. 3 is a front elevational view of FIG. 1 turned 45°.

FIG. 4 is a top plan view of FIG. 3; and,

FIG. 5 is a front elevational view of the cap shown in FIG. 1, the rear elevational view and the side elevational views being the same and not shown.
